CLAIM

The ornamental design for a stair step for a platform, as shown and described.

DESCRIPTION

FIG. 1 is a front elevational view of a stair step for a platform showing my new design;

FIG. 2 is a rear elevational view thereof;

FIG. 3 is a right side elevational view, the left side being a mirror image thereof;

FIG. 4 is a top plan view thereof;

FIG. 5 is a bottom plan view thereof; and,

FIG. 6 is a perspective view thereof.

FIG. 1

FIG. 2

FIG. 3

FIG. 6

FIG. 4

FIG. 5
